UNITED STATES PATENT OFFICE.

SAMUEL H. PETRO, OF DARLINGTON, INDIANA, ASSIGNOR OF ONE-HALF TO
WILSON HUNT, OF SAME PLACE.

INCUBATOR.

SPECIFICATION forming part of Letters Patent No. 446,980, dated February 24, 1891.

Application filed September 18, 1890. Serial No. 365,397. (No model.)

To all whom it may concern:

Be it known that I, SAMUEL H. PETRO, a citizen of the United States, residing at Darlington, in the county of Montgomery and 5 State of Indiana, have invented a new and useful Incubator, of which the following is a specification.

This invention has relation to incubators, the objects in view being to provide a means 10 for controlling the heat within the incubator and maintaining the same at a proper temperature for successfully carrying on the process of incubation.

Other objects and advantages of the invention will appear in the following description, and the novel features thereof will be particularly pointed out in the claim.

Referring to the drawings, Figure 1 is a perspective of an incubator constructed in 15 accordance with my invention. Fig. 2 is a vertical longitudinal section. Fig. 3 is an end elevation. Fig. 4 is a perspective detail of a water-tank.

Like numerals of reference indicate like 20 parts in all the figures of the drawings.

1 designates the incubator-case, provided at its front with the usual hinged door 2, the interior of the case being divided into compartments, as is usual, for the reception of the 25 eggs to be hatched. Above the partitions there is located the water-tank 4, which fits within the outer casing and below the roof of 30 said casing. A hot-air box 5 projects from one end of the water-box through an opening 35 in the casing and over a platform 6, upon which is mounted a lamp 7, the chimney of 40 which passes into an opening 8, formed in the bottom of the hot-air box. The hot-air box communicates with an opening 9 formed in the opposite end of the casing by means of a hot-air pipe 10 extending longitudinally through 45 the water box or tank.

11 designates the cover or roof of the casing, and the same is provided at one end 50 with an extension 12, designed to take over the hot-air box 5, and with a flange 13 depending from the under side thereof and adapted to embrace the hot-air box upon its exposed sides.

55 14 designates a series of (in this instance

four) ventilating-tubes, which extend through the water-tank, and each communicates with a compartment of the incubator. These tubes extend up to corresponding openings 15, formed in the roof 11, and between the two inner tubes of the series there is located in the roof a large opening 16, through which passes a pipe 17, communicating with the interior of the water-tank.

In the pipe 17 there is located a float 18, 60 the stem of which extends up through the roof of the casing and is pivotally connected to the meeting ends of a pair of levers 19, mounted in standards 20 at opposite sides of the opening 16 and between the pairs of openings 15. These levers extend beyond their fulcrums, and one of said levers beyond the extended end of the roof, where it is bent upon itself, as at 21, to form a loop. The loop 21 is connected to the upper end of the connecting-rod 22, which latter at its lower end 65 is loosely pivoted to the lever 23, secured to and extending rigidly from the wick-raising bar 24 of the lamp 7, so that any movement upon the part of the lever as caused by the 70 movements of the float will be transmitted to the wick-raising bar of the lamp, which bar will be rotated partially in accordance with the direction of movement of said lever, and thus the wick raised or lowered. The openings 15 are covered by a series of disks 26, which disks are connected to the lower ends of a series of crank-levers 27. The crank-levers 27 of the two outer disks are fulcrumed in short standards 28, while the crank-levers 80 of the two inner disks are fulcrumed in the standards 20 below the levers 19, and all of the crank-levers have their upper ends terminating under either one of the levers 19.

30 designates a spring-finger secured in 85 the roof of the casing, as at 31, and terminating under the longer lever 19 of the pair in rear of its fulcrum, and therefore having a tendency to raise the same and thus depress the inner ends of the levers and the float, so 90 that pressure from the levers is normally removed from the upper ends of the crank-levers of the disks 26.

In operation the heat from the lamp passes 95 up the chimney thereof into the hot-air box 100

and through the pipe 10 in the water-box to the opposite end of the casing, the water in the box being heated thereby. Should the temperature of the water become too high, 5 the expansion of the water causes the float to rise in the pipe 17, and in so doing the inner ends of the levers 19 are raised and their outer ends consequently depressed. A depression of the outer ends causes a depression 10 of the inner ends of the crank-levers of the disks 26, so that said disks are raised a distance above the openings 15 agreeing with the degree of elevation of the float, and consequently the degree of heat of the water, and 15 the hot air from the compartments permitted to pass through the tubes 14 until said compartments have been sufficiently cooled, whereupon the water in the tank having its temperature lowered contracts and permits 20 the float to fall, which liberates the cranked levers and permits the disks 26 to again cover the openings. As the longer lever 19 is raised at its inner end by the expansion of the water in the tank, it serves to depress the connecting-rod and its arm and partially rotate the 25 wick-operating bar of the burner of the lamp and lower said wick, whereby the flame is decreased, as is also the heat. When the water has been sufficiently cooled, the wick is raised 30 as the float lowers and a reheating takes place. In this manner a proper temperature is automatically maintained in the compartments and incubation facilitated in a successful manner.

35 Having described my invention, what I claim is—

In an incubator, the combination, with the outer casing having a series of chambers and a burner located at the end of the same, of a

water-tank mounted in the upper end of the 40 casing and terminating at one end in a hot-air box in which the chimney of the lamp terminates, and provided with a pipe passing through the tank and communicating with the hot-air box, an opening formed in the 45 roof of the casing, a pipe extending from the tank through the opening, a pair of smaller openings formed in the roof of the casing at each side of said larger opening, tubes passing through the tank and communicating with 50 the chambers or compartments of the incubator and passing through the smaller openings of the roof of the casing, a pair of fulcrumed standards located between each pair of smaller openings, cranked levers mounted 55 upon each standard and each terminating in a disk normally covering one of the smaller openings, a pair of levers fulcrumed upon the inner standards before mentioned, loosely connected at their inner ends with the float 60 and having their outer ends bearing upon the cranked levers, one of said long levers having its outer end bent upon itself to form a loop, an arm extending from the wick-operating bar of the burner, a rod loosely connecting the outer end of the arm with the loop of the before-mentioned lever, and a spring secured to the roof of the casing and terminating under the rear end of one of the levers, substantially as specified.

70 In testimony that I claim the foregoing as my own I have hereto affixed my signature in presence of two witnesses.

SAMUEL H. PETRO.
